DISH BRUSH OR SIMILAR ARTICLE

Leidy G. Scholl, Lansdale, Pa.

Application December 6, 1957, Serial No. 48,822

Term of patent 14 years

(Cl. D9—2)

Figure 1 is a side elevational view of a dish brush or similar article showing my new design;

I claim:

The ornamental design for a dish brush or similar article, as shown and described.
